UNITED STATES PATENT OFFICE.

JOSEPH GAYNOR, OF NEW YORK, N. Y.

TOOTH-BRUSH.

1,007,090.

Specification of Letters Patent.

Patented Oct. 31, 1911.

Application filed August 26, 1911. Serial No. 646,263.

To all whom it may concern:

Be it known that I, JOSEPH GAYNOR, a citizen of the United States, residing at the city of New York, borough of Manhattan, county and State of New York, have invented 5 a new and Improved Tooth-Brush, of which the following is a specification.

This invention relates to a tooth brush of novel construction which is rotated while 10 being moved along the upper or lower row of teeth, and which will thus not only thoroughly clean the teeth but will also effectively brush out the interstices.

In the accompanying drawing: Figure 1 15 is a side view partly in section of a tooth brush embodying my invention; Fig. 2 is a cross section on line 2—2, Fig. 1; Fig. 3 is a cross section on line 3—3, Fig. 1, and Fig. 4 a cross section on line 4—4, Fig. 1.

The tooth brush comprises essentially an 20 apertured plate or bearing 10, to opposite ends of which are pivoted at 11, a pair of handles 12, engaged by a spring 13, that tends to open the handles. To each handle 25 is pivoted at 14, an arched rack 15, having an eye or guide 16 at its inner end, the eye of one rack engaging the body of the other rack. Racks 15 jointly engage a pinion 17 secured to one end of a spindle 18 that is 30 journaled in bearing 10 and held in operative engagement with the racks between eyes 16 by a pair of flanges 19. It will be seen that by closing and opening the handles, the spindle 18 will be alternately rotated in opposite directions. To the free end of spindle 18 is adapted to be coupled the stem 19 of a cylindrical brush 20, for which purpose the spindle is provided with a slotted spring 35

socket 21, the arms of which may be contracted around the end of the spindle by a 40 screw ring 22. A semi-tubular shield 23 secured to bearing 10, encompasses a portion of brush 20 and also extends with its upper rounded end over the outer end thereof, so as to protect the gums against contact therewith. 45

In use, the device is so held that the spindle assumes a substantially horizontal position, and then the brush is passed back and forth over the row of teeth to be cleaned, 50 During this movement the handles 12 are manipulated to rotate the brush, which will thus during its horizontal reciprocation sweep vertically over the teeth, to clean the same thoroughly and to effect at the same 55 time a thorough brushing out of the crevices. Whenever a brush is worn, it may be readily removed and replaced by a new one, so that the change may be effected with very little expense. 60

I claim:

A device of the character described, comprising a bearing plate, a pair of handles pivoted to opposite ends thereof, a pair of curved racks pivoted to the handles, an eye 65 on the inner end of each rack, adapted to engage the body of the other rack, a spindle journaled in the bearing, a pinion on the spindle that is engaged by the racks between the eyes and a cylindrical brush secured to 70 the spindle.

JOSEPH GAYNOR.
